Primary Examiner — Patricia A Palasik(74) *Attorney, Agent, or Firm* — Calfee, Halter & Griswold LLP(57) **CLAIM**

We claim the ornamental design for a picture-book reading robot, as shown and described.

DESCRIPTION

FIG. 1 is a front elevational view of a picture-book reading robot of the present design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a top/front/right perspective view thereof.

The broken lines are for purposes of illustrating portions of the picture-book reading robot which form no part of the claimed design.

1 Claim, 5 Drawing Sheets(56)
